SIMULATED FLUSH PULL

William Doyle Watt, Jr., Grand Rapids, Mich., assignor to
Keeler Brass Company, Grand Rapids, Mich.

Filed Mar. 15, 1971, Ser. No. 124,612

Term of patent 14 years

Int. Cl. D8—06

U.S. Cl. D8—158

FIG. 1.

FIG. 2.

FIG. 3.

FIG. 4.

FIG. 1 is a perspective view of the simulated flush pull embodying my new design;

FIG. 2 is a perspective view of the simulated flush pull seen in FIG. 1;

FIG. 3 is a side elevational view of the simulated flush pull shown in FIGS. 1 and 2; and

FIG. 4 is a sectional view taken along line IV—IV of FIG. 1.

I claim:

The ornamental design for a simulated flush pull, substantially as shown.
